CLAIM

The ornamental design for a reader, as shown and described.

DESCRIPTION

FIG. 1 is a top front perspective view of a reader according to an exemplary embodiment of the present design.

FIG. 2 is a top view of the reader of FIG. 1.

FIG. 3 is a bottom view of the reader of FIG. 1.

FIG. 4 is a front view the reader of FIG. 1.

FIG. 5 is a back view of the reader of FIG. 1.

FIG. 6 is a right side view of the reader of FIG. 1.

FIG. 7 is a left side view of the reader of FIG. 1.

FIG. 8 is a top rear perspective view of the reader of FIG. 1.

FIG. 9 is a top front perspective view of the reader of FIG. 1 in an open configuration.

FIG. 10 is a top view of the reader of FIG. 9.

FIG. 11 is a bottom view of the reader of FIG. 9.

FIG. 12 is a front view the reader of FIG. 9.

FIG. 13 is a back view of the reader of FIG. 9.

FIG. 14 is a right side view of the reader of FIG. 9.

FIG. 15 is a left side view of the reader of FIG. 9; and, FIG. 16 is a top rear perspective view of the reader of FIG. 9.

The broken lines are directed to unclaimed features of the reader and form no part of the claimed design.

1 Claim, 10 Drawing Sheets
